DESIGN FOR A SEPARABLE BROOCH

Gene Verrecchio, Providence, R. I., assignor to
Cohn & Rosenberger, Inc., New York, N. Y., a
corporation of New York

Application February 19, 1942, Serial No. 105,913

Term of patent 3½ years

To all whom it may concern:

Be it known that I, Gene Verrecchio, a citizen
of the United States of America, residing in
Providence, county of Providence, and State of
Rhode Island, have invented a new, original, and
ornamental Design for a Separable Brooch, of
which the following is a specification, reference
being had to the accompanying drawing, forming
part thereof.

Fig. 1 is a plan view of a separable brooch
showing my new design.

Fig. 2 is an edge view thereof.

Fig. 3 is a plan view as shown in Fig. 1, showing
the brooch in separate positions.

I claim:

The ornamental design for a separable brooch,
as shown and described.

GENE VERRECCHIO.
